UNITED STATES PATENT OFFICE

GEOERGE O. MURRAY, OF BLAIRSVILLE, PENNSYLVANIA

DESIGN FOR A COMBINATION STOVE, REFRIGERATOR, AND SINK

Application filed February 14, 1930. Serial No. 34,556. Term of patent 3½ years.

To all whom it may concern:

Be it known that I, GEORGE O. MURRAY, a citizen of the United States, residing at Blairsville, in the county of Indiana and State of Pennsylvania, have invented a new, original, and ornamental Design for a Combination Stove, Refrigerator, and Sink, of which the following is a specification, reference being had to the accompanying drawing, forming part thereof.

The figure is a perspective view of a combination stove, refrigerator and sink, showing my new design.

I claim:

The ornamental design for a combination stove, refrigerator and sink as shown.

GEORGE O. MURRAY.
